UNITED STATES PATENT OFFICE.

JOHN W. ULREY, OF NORTH MANCHESTER, INDIANA.

DESIGN FOR A FENCE-POST.

SPECIFICATION forming part of Design No. 35,171, dated October 8, 1901.

Application filed August 31, 1901. Serial No. 74,045. Term of patent 7 years.

To all whom it may concern:

Be it known that I, JOHN W. ULREY, a citizen of the United States, residing at and whose post-office address is North Manchester, in the county of Wabash and State of Indiana, have invented and produced a new and original Design for a Fence-Post, of which the following is a specification, the construction being illustrated in the accompanying drawings.

10 My invention is a design for fence-posts; and it consists of the shape and configuration illustrated in the accompanying drawings, in which—

15 Figure 1 is a front elevation of a fence-post embodying the design. Fig. 2 is a side view of the same. Fig. 3 is a rear elevation, and Fig. 4 is a horizontal section on the line 4-4 of Fig. 1 on an enlarged scale.

20 The reference-numeral 1 designates the body of the post, which is slightly tapered from a point 2 near its lower end to its upper end. From the point 2 to the base 3 the sides of the body are inwardly curved, as at 4. Projecting centrally from the back of the 25 body is a rib 5, extending only part of the length of the post, and on either side of said rib 5 the body 1 is formed with a vertical row of perforations 6.

7 designates a flange projecting centrally from the front of the body 1 at right angles 30 thereto and, like the sides of the body, tapering upward from a point 8 near the base to its upper end and inwardly curved, as at 9, below the point 8. A base-flange 10 connects the lower ends of the flange 7 and the body 1. 35

11 and 12 designate rounded ribs or projections extending vertically on opposite sides of the flange 7 and at its points of juncture with the body. These ribs extend nearly the entire length of the post and are rounded or 40 tapered off at their ends.

The leading features of the design are the inwardly-curved lower portions of the body and flange 7, the vertically-disposed ribs 5, 11, and 12, and the base-flange 10. 45

I claim—

The design for a fence-post herein shown and described.

In testimony whereof I affix my signature in presence of two witnesses.

JOHN W. ULREY.
